PUNCH PRESS

James T. Gramling, Shawnee, Kans., assignor to Gramling Tool & Die, Inc., Overland Park, Kans.

Filed Aug. 31, 1972, Ser. No. 285,326

Term of patent 14 years

Int. Cl. D15—09

U.S. Cl. D63—1

FIG. 1 is a top plan view of a punch press showing my new design;

FIG. 2 is a side elevational view of the punch press;

FIG. 3 is a front view of the punch press; and

FIG. 4 is a rear view of the punch press.

I claim:

The ornamental design for a punch press, as shown and described.
